(57) **CLAIM**

The ornamental design for a combined snap assembly actuator housing and mounting bracket, as shown.

DESCRIPTION

FIG. 1 is a perspective view of a combined snap assembly actuator housing and mounting bracket showing the new design;

FIG. 2 is a front view of the combined snap assembly actuator housing and mounting bracket of FIG. 1;

FIG. 3 is a back view of the combined snap assembly actuator housing and mounting bracket of FIG. 1;

FIG. 4 is a side view of the combined snap assembly actuator housing and mounting bracket of FIG. 1;

FIG. 5 is a bottom view of the combined snap assembly actuator housing and mounting bracket of FIG. 1;

FIG. 6 is a top view of the combined snap assembly actuator housing and mounting bracket of FIG. 1;

FIG. 7 is a perspective view of A combined snap assembly actuator housing and mounting bracket showing the new design;

FIG. 8 is a top view of the combined snap assembly actuator housing and mounting bracket of FIG. 7;

FIG. 9 is a bottom view of the combined snap assembly actuator housing and mounting bracket of FIG. 7;

FIG. 10 is a front view of the combined snap assembly actuator housing and mounting bracket of FIG. 7;

FIG. 11 is a top view of the combined snap assembly actuator housing and mounting bracket of FIG. 7;

FIG. 12 is a back view of the combined snap assembly actuator housing and mounting bracket of FIG. 7;

FIG. 13 is a perspective view of a combined snap assembly actuator housing and mounting bracket showing the new design;

FIG. 14 is a front view of the combined snap assembly actuator housing and mounting bracket snap assembly of FIG. 13;

FIG. 15 is a back view of the combined snap assembly actuator housing and mounting bracket of FIG. 13;

FIG. 16 is a side view of the combined snap assembly actuator housing and mounting bracket of FIG. 13;

FIG. 17 is a top view of the combined snap assembly actuator housing and mounting bracket of FIG. 13; and,

FIG. 18 is a bottom view of the combined snap assembly actuator housing and mounting bracket of FIG. 13.

The portions of the Figures shown in phantom lines are not part of the claimed design but are for illustration only.
